UNITED STATES PATENT OFFICE.

GEORGE W. STAFFORD, OF PROVIDENCE, RHODE ISLAND, ASSIGNOR TO
THE CROMPTON & KNOWLES LOOM WORKS, OF SAME PLACE.

DOBBY FOR LOOMS.

SPECIFICATION forming part of Letters Patent No. 634,632, dated October 10, 1899.

Application filed June 26, 1899. Serial No. 721,857. (No model.)

To all whom it may concern:

Be it known that I, GEORGE W. STAFFORD, a citizen of the United States, residing at Providence, in the county of Providence and State of Rhode Island, have invented certain new and useful Improvements in Dobbies for Looms, of which the following is a specification, reference being had therein to the accompanying drawings.

10 The invention has relation to the devices which are employed in dobbies for the purpose of actuating the knives or lifters by means of which the jack-hooks are engaged and moved to operate the harness-levers and harness-frames.

More particularly the invention involves the hooked rods or links which connect the respective ends of each knife or lifter with the corresponding arms of the actuating-rockers. 20 In the case of the old form of the said hooked rods or links upon which I have improved one end of each thereof is merely turned down to form a simple hook, the latter engaging with an eye or the like that is provided at the end 25 of the knife or lifter. In operation the convex or outer side of the hook takes bearing against the interior of the eye in pushing the knife or lifter in one direction. In time the eye becomes worn to such an extent that the 30 hook is permitted to slip out of place, which results in the ensuing movement in breakage of either the hook or the eye.

The object of the invention is to provide a rod or link having a form of hook which will 35 be free from tendency to slip out of position and to occasion breakage in consequence of the wear aforesaid.

The accompanying drawings illustrate a practical embodiment of the invention and 40 also present by way of contrast the old form of hook which my invention is designed to supersede.

In the drawings, Figure 1 shows in side elevation a portion of a dobbey having the said 45 embodiment of the invention applied thereto. Only such parts of the dobbey are shown as are required to be presented in order to make clear the nature and relations of the invention. Fig. 2 is a detail view showing the old 50 form of hooked rod or link.

Reference will be had first to the parts in general which are shown in Fig. 1. a designates a portion of the dobbey-frame, and a' the pattern-cylinder. The rocker at one side of the dobbey is shown at a^2 , the swivel applied to the 55 lower arm of the said rocker being shown at a^3 . a^4 is a hooked rod or link, it having its stem passed through the said swivel and adjustably secured relatively thereto by means of the nuts a^5 upon the screw-threaded portion of the 60 said stem at opposite sides of the swivel. a^6 is the hooked end of the said rod or link. a^7 is the eye or its equivalent, in which the said hooked end of the rod or link a^4 engages, and a^8 is one of the knives or lifters, it being provided 65 at the end thereof which is shown in Fig. 1 with the said eye a^7 . The slot or guide-way in which the end of knife or lifter a^8 moves is designated a^9 .

Having reference to Fig. 2, the hooked rod 70 or link therein is designated a^{10} and is of the old form to which reference has been made hereinbefore. It will be perceived that, as stated, the hook a^{11} thereof is formed merely by turning down the end of the rod or link 75 into a simple hook having its convex side turned outermost, so that the push by which the movement of the knife or lifter in one direction is occasioned is transmitted by the said convex side to the eye of the knife or 80 lifter.

It will be understood that in the form of dobbey which is partially represented in the drawings it is in the outward movement of the knife or lifter that the latter does its main 85 work—i. e., engages with the selected jack-hooks and carries them outward for the purpose of operating the corresponding harness-levers and raising the required harness-frames. The main resistance to the movement 90 of the knife or lifter, tending to occasion wear between the eye a^7 and the hook working therein, therefore, in the said form of dobbey, is encountered in the outward movement of the parts.

The tendency of the hook a^{11} in Fig. 2 to 95 work out of place will increase in proportion as the parts wear at the places of contact.

The characteristic of the improved hook a^6 (shown in Fig. 1) is the fact that it is recurved 100

or reversed, whereby the convex side thereof is presented toward the rocker a^2 , so that in the movement which carries the knife or lifter a^8 outwardly the push is transmitted by the concave side of the hook a^6 to the eye a^7 . It will be perceived that the form of the said improved hook a^6 is such that it fits securely in place in eye a^7 and merely rocks slightly in the said eye in consequence of the curvilinear path of the point of connection of the hooked rod or link a^4 with the rocker. It cannot by any possibility, in consequence of any amount of wear, work out of place, so as to occasion breakage.

I claim as my invention—

In a loom-dobby, in combination, the rocker, the knife or lifter having an eye, as a^7 , and the rod or link a^4 connected with the said rocker and having the reversed or recurved hook a^6 working in the said eye to transmit movement from the rocker to the knife or lifter.

In testimony whereof I affix my signature in presence of two witnesses.

GEORGE W. STAFFORD.
